INVENTOR

BY *Victor J. Evans*

ATTORNEY

WITNESS:

John Donoran

UNITED STATES PATENT OFFICE.

OSCAR G. SHILANDER, OF DEARBORN, MICHIGAN.

RACK.

Application filed January 16, 1926. Serial No. 81,818.

This invention relates to a rack for holding hats and the like, the general object of the invention being to provide a rack which can be manufactured to sell at low cost and one which cannot collect dust and which can be folded into a small space when not in use.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a plan view showing the rack in use.

Figure 2 is a section on line 2—2 of Figure 1.

Figure 3 is a view of an end of one of the braces.

Figure 4 is a view of one of the hinged clips.

In these views, 1 indicates a rectangular shaped frame and 2 indicates transversely and longitudinally extending strips having their ends connected with the frame, preferably by spot welding, as shown at 3. These strips are spaced apart to form a net-like frame which will support hats and the like, while presenting small areas for catching dust. A pair of clips 4 hingedly supports the frame from a wall or the like, each clip being formed of a strip of metal bent upon itself to form an eye 5 through which the rear bar of the frame passes, the clip having a hole 6 therein so that a screw can be passed through the same into the wall. A pair of brace bars 7 each has an eye 8 at one end for receiving the front bar of the frame, and its other end is bent downwardly and flattened and provided

with a perforation 9 for receiving a screw or the like to fasten this end of the brace to the wall.

These braces hold the frame in horizontal position so that hats or the like can be placed on the same. By taking out the fastening means at the lower ends of the braces, the frame can be swung against the wall in either direction so that it will be out of the way, and by folding the braces against the frames, a plurality of frames can be placed together and shipped or stored without occupying much space.

This invention is mainly designed for use in clothes closets and it may be placed over the door to hold hats and suitcases or on the baseboard for holding shoes.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:

A supporting rack of the class described comprising a rectangular-shaped frame formed of round stock, spaced straps extending transversely and longitudinally across the frame with their ends fastened to the frame, the longitudinally extending straps passing under alternate transversely arranged straps and over the other transversely arranged straps, eye forming clips connected with the rear bar of the frame for hingedly connecting the frame with a support and a pair of braces each having an eye at one end receiving a part of the front bar of the frame and its other end bent at an angle and flattened for attachment to a support.

In testimony whereof I affix my signature.

OSCAR G. SHILANDER.
